MEANS FOR STACKING ARTICLES

Jacob R. Jason, New York, N. Y.

Application April 18, 1940, Serial No. 330,386

5 Claims. (Cl. 206—9)

This invention pertains to improvements in packaging rimmed articles, for example such as hats. Particularly the invention relates to means to support a series of such rimmed articles stacked one above the other but separate from each other. In particular, the present invention may be illustrated by a stack of hats in a hat box out of substantial contact with each other and suspended in such a way as not to acquire creases or dents or marks on the hats.

A purpose of this invention is to suspend a hat, for example, by the inner band or other rimmed portion, by means which combine extreme simplicity of manufacture with adjustability to various positions in a container. A purpose moreover is to affix a suspending element in simple manner so as to utilize the walls of the container to impart flexibility of position to the supporting elements. These and other objects will be apparent in the ensuing description of this invention taken with the accompanying drawings of preferred embodiments of the invention. The invention will be more fully pointed out in the appended claims.

In the drawings:

Figure 1 shows in vertical section a plurality of hats suspended or stacked one above the other but out of contact with each other;

Figure 2 shows in top plan view a hat supported by the wall of a container and by an arm extending therefrom;

Figure 3 illustrates a modification of this invention in vertical perspective in which some flexibility of horizontal position is imparted by the walls of the container to a suspending element;

Figure 4 shows a cross section through a container wall with a suspending element in plan view;

Figure 5 is a perspective view of a double supporting element taken alone;

Figure 6 is a perspective view of a double supporting element embodying a modification to accomplish adjustability of the arms of the element;

Figure 7 is a perspective view of a single arm of a supporting element having an adjustable arm;

Figure 8 is a perspective view of a modification of a single arm of a supporting element having an adjustable arm.

According to this invention, a container wall is provided in which are staple-like eyes with a vertical supporting base fitting through the eye and bearing against the wall of the container.

Thus is formed a base leverage to support a horizontal arm and terminal vertical loop for engaging the rim of a hat or other article to be stacked. Various specific modifications of this invention will be illustrated.

The invention is designed to support rimmed articles by engagement at the inner edge of the rim by means of brackets. The brackets are spaced horizontally to engage the inner part of the rim at separated points, usually at opposite positions and the brackets are attached at the outer ends to supporting means such as the walls of a box or riser elements such as vertical standards in the case of heavy articles. This latter construction enables the articles to be placed on the brackets and the brackets then detachably or permanently secured on riser elements. The brackets are preferably long enough to space the outer parts of the article from the riser elements.

In Figures 1, 2 and 3, a container is shown having a flexible wall 1. Inserted through the wall are simple wire eyelets to form loops 2 at suitable positions. In preferred form as shown loops 2 are horizontal. The wall is shown with an inner panel flexibly attached thereto in the area through which the eyelets extend. This may be accomplished by affixing a piece of flexible material, such for example, as an additional piece of cardboard 3 similar to that of the container wall. This is shown particularly in Figure 3 to be stapled in simple manner to the inside of the container wall so as to afford some measure of flexibility or some amount of bulging inwardly to attain slight adjustment horizontally of the arms in which the rimmed articles are to be supported.

Through staples 2 are inserted vertical loops 4 forming the base of a wire supporting arm. The loop base rests against the cardboard. Extending horizontally therefrom at the top of the loop is horizontal arm 5 of the wire support, terminating inwardly in a double loop; that is to say, in a vertical looped portion 6. This rising loop is adapted to fit under the rimmed portion of the article to be supported. In the form shown, the supporting arm is double with a pair of vertical base loops 4 instead of a single base. These terminate inwardly in the common vertical loop 6.

As applied to hats as shown in Figures 1 and 2, the horizontal arms 5 converge so that the inner loop 6 rises to slip under the inner hat band 7 at opposite sides of the hat.

With a series of hats, the weight imposed on the inner supplemental wall piece 3 results in flexibility such that the arms 5 may move away

from the wall of the container in some slight degree to accommodate various hat sizes.

However, accommodation may be accomplished with a modification of the invention in which horizontal arms 5 themselves are variable in their extension away from the wall. Such are illustrated in Figures 6 and 7.

In Figure 6 horizontal arms 5 are in two separate parts. One portion 5a terminates in a coil 8 which may be more or less spring-like. The other portion 5b extends through the coil of the portion 5a and at the end is upset or enlarged so as not to slide out of the coil. Thus the rigidity of the arm 5 is maintained, but the arm is extensible. In this way not only is the loop 6 common to the horizontal arm adjusted to different hat sizes, but the arms also accommodate themselves to differences in width of brim of hat. In this way, an exceedingly simple and inexpensive form of support is adapted for packaging of such diverse forms of hat as a derby, for example, in the same box with a broad-brimmed "Stetson." Nevertheless, on some other occasion the entire series of hats may be of one kind but yet the supporting arms are readily adjustable thereto.

A structural advantage that may be embodied in this invention is illustrated in Figure 6. The riser portions 10 of the staple-engaging loop 4 is terminated in an end that is directed away from the supporting staple toward the inner portion of the container. Thus a person may readily grasp the free leg 10 of the staple-engaging loop so as to press the loop for insertion or for removal from the staple. This structural advantage may be embodied not only in the particular form illustrated in Figure 6 but in other modifications of this invention.

In another form of extensible arm shown in Figure 7, arm 5 is in two parts 5c and 5d, which terminate in overlapping relationship to each other. The two ends are held in assembly by an encircling coil 9. The coil is held from slipping off from either of the ends 5c or 5d by a suitable stop at the end of each arm. In Figure 7, the ends of the coil 9 terminate in discs while the respective arm ends extend through the corresponding discs and are enlarged or upset so as not to be withdrawable through those discs. In the form shown in Figure 7, a single arm is shown but this showing is not intended as a limitation. A single arm as shown may be used or a similar construction may be presented in double armed retainer such as illustrated in Figures 5 and 6, for example.

Figure 8 shows another modification to illustrate the variety of forms of arm 5 that are appropriate. In the Figure 8 modification, in which arm 5 is in two parts—5e and 5f—each part terminates in a simple loop that encircles the straight portion of the other end, 5f and 5e respectively. Thus the two ends are held close to each other, but rigid horizontally and yet extensible horizontally.

In the various forms of arm, the vertical base portion 4 is desirably crimped to include a latch projection 10. This is preferably in the free end of base loop 4 so that the loop may be pinched together at the top to slide through retaining eye 2 on the wall of the container but fly back on release. Thus the retainer base resists inadvertent removal from the supporting loop 2 but yet consists of an exceedingly simple and inexpensive structure.

In thus describing this invention, the forms

shown are not intended to be limiting but to be illustrative. The particular wire arms are exceedingly simple in form and simple to manufacture and are inexpensive. This adds considerably to utility in the field of use illustrated, inasmuch as exceedingly inexpensive containers are requisite. Moreover, in the form shown with the loop eye, these retaining arms are easy to apply. Cheap labor may insert the required fastening staples to the container wall. Moreover, in convenience such forms of looped retaining arms excel because readily removable or readily interchangeable if need be. In the extensible forms illustrated by Figures 6 and 7, there is at once accommodation to various hat sizes and brim sizes. Further, resilience of the panel mounting taken with resilience of the light wire arms aids in relieving the hats from pressure or wear marks. An objection to many previous forms of hat supports has been the fact that they cause marks gradually to appear on hats supported thereby.

This invention has been illustrated with reference to the stacking of hats and to such use the invention is particularly valuable, but this invention is applicable to other articles that involve similar problems. For example, lamp shades are similar delicate articles that require care in packing. On the other hand, ease and adaptability as found in this invention may be useful when such relatively heavy articles as automobile tires are to be supported on opposed arms, particularly where adjustability and extensibility of the arms are desirable.

Although I have described this invention in accordance with the patent statutes and have illustrated its principles by reference to a practice that is at present preferred, it will now be apparent to those skilled in this art that alterations and changes of detail are possible within the scope of the appended claims.

What I claim is:

1. Hat hanger adapted to be used in opposed pairs to suspend a hat in a hat box, comprising a resilient bent wire member having its hatward end including a middle loop with bight upstanding adapted to engage behind the sweat band of an inverted hat, and wire portions adjacent the lower ends of the sides of said middle loop bent upward and outward substantially in a vertical plane, and having a boxward end comprising a pair of loops with downwardly extending bights adapted to seat in horizontally disposed retaining sockets on the side of a hat box, and horizontal arms connecting said downwardly extending loops to said vertically disposed wire portions, said arms diverging in a boxward direction at such repose angle as to space the downwardly extending loops a greater distance apart than the sockets with which they are designed to cooperate.

2. Hat hanger as claimed in claim 1, said arms being sectional, one section being formed into a resilient coil, the other section being slidable through said coil and frictionally gripped thereby.

3. Hat hanger as claimed in claim 1, said arms being sectional, with adjacent end portions of the sections lapping, and compression springs retained between said lapping portions resisting elongation of said arms.

4. Furnishing for a hat box adapted to be used in plurality for suspending a hat out of contact with the walls of the hat box comprising a panel adapted to be secured in upright position to the inside of the wall of the hat box having a horizontal loop projecting from the inner side thereof,

and a hat support comprising a base portion having the form of an open resilient loop adapted to slip compressively within said panel loop and to bear against said panel, a substantially horizontal arm continuous with said open loop and extending inwardly therefrom a distance greater than the width of the hat brim having a down-

wardly extending inner portion the terminal part of which is diverted upwardly to engage within the sweat band.

5 5. Furnishing for a hat box as claimed in claim 4, said substantially horizontal arm being formed of sections extensibly connected.

JACOB R. JASON.
